BEACH SHELTER

Charles L. Jolly, Wilmar, Calif., assignor of one-third to Mabel C. Olin, Los Angeles, Calif.

Application December 22, 1932, Serial No. 648,426
Renewed February 26, 1934

16 Claims. (Cl. 135—7.1)

My invention relates to a collapsible shelter for use on beaches or the like in which a rib or bowed structure with fabric stretched between the ribs or bows may be opened or extended to form a shelter which may be folded or collapsed for carrying to and from the place of use.

In this type of shelter an object and feature of my invention is a construction by which the shelter may be supported and stretched between a pair of posts or stakes separated apart by the length of the shelter and in which the shelter may be adjusted vertically on the posts.

A further object and feature of my invention is forming the shelter with a plurality of bows or ribs, the ends of the bows being pivotally connected to adjustable clamps which may be placed at any desired elevation on the stakes.

A further feature of my invention is the employment of a readily engageable and disengageable spring which may be used to extend the bows apart so that the fabric covering between the bows forms a shelter. By this construction therefore the ends of the bows converge to the pivot when the shelter is extended and thus the pivot ends may be readily attached to the clamps.

Another detail feature of my invention relates to the combinational clamps and hub structure by which the ends of the bows are secured in a socket device in a hub structure and this is secured to the clamps, the tightening of the clamps therefore holding the bows in their desired extended position.

My invention is illustrated in connection with the accompanying drawing, in which

Fig. 1 is a side elevation taken in the direction of the arrow 1 in Fig. 2.

Fig. 2 is a front elevation taken in the direction of the arrow 2 of Fig. 1.

Fig. 3 is a vertical section on the line 3—3 of Fig. 1 or Fig. 4, in the direction of the arrows.

Fig. 4 is a horizontal section on the line 4—4 of Fig. 3, in the direction of the arrows.

Fig. 5 is a vertical detail section on the line 5—5 of Fig. 3 in the direction of the arrows.

Fig. 6 is a partial elevation illustrating the attachment of the spring to one edge of the shelter.

As illustrated, the shelter has end ribs or bows 11 and intermediate ribs or bows 12, these being arched. Each of the bows has opposite outwardly bent ends 13. Between the bows there is a fabric covering 14, and this fabric is so shaped that the ends of the bows fit close together.

A housing for the bows comprises a hub structure 15 which has a cylindrical section 16 with a bent-in flange 17 and an outwardly extending

disc 18. This disc at the lower portion has a flange 19. Inside the cylindrical section there are a pair of shoulders 20 and resting on these shoulders there is an arcuate plate 21 having straight ends 22, these latter fitting on the shoulders 20. This construction therefore forms an arcuate socket 23 in which the outwardly bent ends 13 of the bows or ribs fit.

The structure for supporting the shelter comprises a pair of posts or stakes 24 which may be driven into the ground and for this purpose are shown as having a coarse thread 25, the ground level being indicated at 26. Fitting around each stake there is a clamp 27, each clamp having a circular portion 28, a short arm 29 and a longer arm 30 parallel thereto. Each of these arms is provided with a perforation 31 through which extends the shank 32 of a bolt, the head 33 of which fits against the short arm 29. The inwardly turned flange 17 provides an opening through which extends the shank 32 of the bolt, and on this bolt there is a disc 34 which has an outwardly flared edge 35. A thumb operated nut 36 is threaded on the shank of the bolt and bears against the disc 34, thus through the medium of the head 33 exerting a clamping action on the arms 29 and 30 and the circular section 28 of the clamp. This action of tightening the clamp also secures the section 36 of the bows adjacent their ends between the arm 30 and the disc-like portion 18 of the hub and holds the bent ends 13 of the ribs in the socket structure 23, which socket is formed by the cylindrical section 16 of the hub and the inserted arcuate plate 21.

In order to stretch or extend the bows or ribs 35 adjacent each end bow 11 on opposite sides there is a grommet 37. A spring 38 has a central portion 39 coiled one or more turns around the cylindrical section 16 of the hub. This spring has a pair of arms 40 which extend outwardly substantially tangentially from the cylindrical section 16 of the hub, and these normally may be at a considerably obtuse angle one to the other or they may be in alignment. Each arm has a hook 41 which may be fitted in a grommet 37. Thus, one of the hooks 41 may be fitted in one of the grommets, the base may be spread apart by hand and the opposite arm bent from the full line position of Fig. 5 to the dotted line position, or from the dotted to the full line position of Fig. 1, and thus hold the bows and the fabric cover spread or extended. As shown in Fig. 1, the shelter forms an arc of slightly more than ninety degrees. Manifestly this may be changed to be either more or less.

From the above description it will be seen that the shelter is readily assembled, the ends of the bows being readily insertable in the sockets attached to the hubs, which hubs are used to 5 tighten the clamps on the stakes. Therefore, the height of the shelter above the ground line may be readily changed within the limits of the stakes, and on account of the springs at each end coiled around each hub and having the two arms 10 the shelter is always held in an extended position when in use. If desired the thumb nut may be clamped sufficiently tight to secure the portions 36 of the hubs or bows between the plate 30 and the disc 18 sufficiently tight so that the 15 shelter is held or maintained in the desired extended position without necessitating spreading the shelter by means of the spring 38.

Various changes may be made in the principles of my invention without departing from the spirit 20 thereof, as set forth in the description, drawing and claims.

I claim:

1. A shelter comprising in combination a pair of stakes, a plurality of bows having fabric thereon, a clamp for each stake, a pivot structure connected to each clamp for pivoting the ends of the bows whereby the bows may be collapsed or folded or extended, the tightening of the clamp retaining the pivoted ends of the bows in adjusted position.
2. A shelter as claimed in claim 1, and means to extend the bows comprising a spring engaging a plurality of bows and tensioned to force said bows apart.
3. A shelter comprising in combination a pair of stakes, a clamp for each stake, a hub structure attached to each clamp, each hub structure having a pivot means for engaging the ends of a plurality of bows whereby the bows may be collapsed or folded together, or spread apart, said bows having a fabric cover.
4. A shelter as claimed in claim 3, and a means to extend the bows comprising a spring fitted on at least one of the hubs and having means to engage at least two bows and tensioned to force said bows into extended position.
5. A shelter comprising in combination a pair of stakes, a clamp secured to each stake, a hollow hub structure secured to each clamp, each hub structure having a socket, a plurality of bows having fabric therebetween, each bow having its opposite ends fitting in a socket.
6. A shelter as claimed in claim 5, and a means to extend the bows comprising a spring coiled on each hub structure, each spring having an arm, and means to engage the free ends of the arms with the two extreme bows.
7. A shelter comprising in combination a pair of stakes, a clamp for each stake having a bolt, 60 a hollow hub structure mounted on each bolt, each hub structure having a socket, a plurality of bows having fabric therebetween, the ends of each bow fitting in a socket, and a nut on each bolt to tighten the hub on the clamp and secure 65 each clamp to a stake.

8. A shelter as claimed in claim 7, each socket being formed concentric to the adjacent bolt and each bow having an outwardly bent end to fit in the socket.

9. A shelter as claimed in claim 7, and means 5 to spread the bows and fabric comprising a spring coiled on at least one of the hubs, said spring having arms with hooks, and the fabric adjacent the two extreme bows having grommets to engage the said hooks, the spring being under tension to 10 extend the bows and hence the fabric.

10. A shelter comprising in combination a pair of clamps each adapted to engage a stake, each clamp having an arm, a bolt extending therethrough, a hollow hub on each bolt and having a 15 socket, a plurality of bows having fabric thereon, the ends of the bows fitting in a socket and the portion of the bows adjacent the ends fitting between the said arm and the hub.

11. A shelter as claimed in claim 10, the exterior 20 of the hubs being cylindrical and one of the hubs having a spring coiled thereabouts with a pair of outwardly extending arms, and means to connect each arm to the two extreme bows.

12. A shelter comprising in combination a pair 25 of clamps each having means to encircle a stake, and each having a pair of arms with a bolt extending through said arms, a hollow cylindrical hub on each bolt having an outwardly extending disc, each hub having a socket, a plurality of bows 30 with fabric thereon, the ends of the bows being outwardly bent to fit in a socket and the portion adjacent such ends fitting between one of the arms and the said disc, and a nut on the bolt to tighten the said arms and the clamp together and 35 to press the hub against one of the arms of the clamp.

13. A shelter as claimed in claim 12, the bolt having a loose disc thereon under the nut, a spring coiled on the cylindrical section of the hub 40 between the loose disc and the disc of the hub, each spring having a pair of outwardly extending arms with a hook on the end, the fabric adjacent the two extreme bows having grommets to engage the said hooks.

14. A shelter as claimed in claim 12, the said 45 socket being formed by an arcuate plate, a pair of shoulders to support said plate, the plate forming an arcuate socket concentric to the bolt.

15. A shelter comprising, in combination, a 50 plurality of bows, each of substantially the same arc, having flexible material secured thereto, a pair of clamps, a pivot structure connected to each clamp, said bows having associated ends and said bow ends being respectively secured to the 55 pivot structures, and means for tightening the clamp and retaining the pivoted ends of the bows in adjusted positions.

16. A shelter as claimed in claim 15, a spring 60 engaging each pivot structure and the two outside bows, and tensioned to force the bows apart and hold the shelter in an extended position.
